UNITED STATES PATENT OFFICE.

ROMAN WINOGRAD AND SAMUEL SHAKIN, OF NEW YORK, N. Y.

TOOTHBRUSH HOLDER.

Application filed March 31, 1925. Serial No. 19,669.

To all whom it may concern:

Be it known that we, ROMAN WINOGRAD and SAMUEL SHAKIN, citizens of the United States, and residents of New York, in the county of Bronx and State of New York, have invented certain new and useful Improvements in Toothbrush Holders, of which the following is a specification.

This invention relates to tooth brush holders, particularly the kind which provide an individual housing for a tooth brush to protect the same from falling dust and to prevent the bristle portion of the brush to come in contact with other brushes or articles.

It is one of the objects of the invention to provide a bracket of extremely simple construction for the support of such an aforesaid housing.

Another object is to make this bracket especially suitable for use in connection with a commercial glass tube which may be used for housing the brush.

A further object is to provide means in connection with the bracket which enable the housing, after having been removed from the bracket for cleaning or other purposes, to be replaced in the most advantageous position with respect to it, without any difficulty or accurate adjustment.

A still further object is to provide a tooth brush holder of the character described which can be economically manufactured, comprising the least possible number of parts, and which can be applied to actual use by any person, not necessarily with mechanical experience.

Still other objects will become apparent in the following specification and its accompanying drawings, in which

Fig. 1 is a front elevational view of the tooth brush holder complete;

Fig. 2 is a sectional view of the same, taken along the plane of line 2—2, in Fig. 1, showing a tooth brush in dotted lines;

Fig. 3 is a plan view of the holder; and

Fig. 4 a cross sectional view taken along the plane of line 4—4, in Fig. 1.

Like characters of reference denote similar parts throughout the several views.

10 is a housing or glass tube of the kind customarily used as a test tube, and commercially obtainable in the market as such, having a cylindrical body portion 11 of the same diameter throughout its length, and

its top closed at 12 and its bottom open at 13.

14 is a bracket, consisting of a vertically disposed standard 15, having at its upper end two outwardly extending curved arms 16 and 16^a, so shaped as to embrace snugly 60 the cylindrical portion 11 of the housing 10, and connected to the standard in a U-shaped cross section, as shown at 17, in order to keep the housing 10 a little distance away from the standard to allow clearance for 65 screw heads, as will be apparent hereafter. The lower end of the standard 15 is also bent outwardly at, preferably, right angles thereto, at 18, and is slightly cup-shaped at 19. The bracket 14 is, preferably, made of 70 a sheet metal stamping and is particularly designed with this end in view, so that the same may be manufactured very cheaply and produced in large quantities.

In about the center of the standard 15, a 75 prong 20 is provided for, bent outwardly at substantially right angles to the standard. This prong is stamped out of the standard, leaving a rectangular opening 21 therein. The prong 20 projects outwardly far enough 80 to form a support for the lower end of the housing 10. 22 is an opening for a screw to fasten the bracket 14 to a wall, located in the standard 15 between the arms 16 and 16^a and prong 20. 85

22 is a tooth brush, indicated in Fig. 2, in dotted lines.

The method of using our improved tooth brush holder is as follows:

The tooth brush 22 is placed in the position, shown in Fig. 2, so that its brush portion will be within the housing 10. The extreme end of its handle part rests within the cup-shaped portion 19 of the bracket 14. In this position the brush will be protected 90 from falling dust, or from contacting with other brushes or articles, resulting in a sanitary storage of the brush. 95

It will be noted that the arms 16 and 16^a which have certain springy properties owing to its construction and material, snugly embrace the housing 10 and being of considerable width hold and guide the same securely in a vertical position. The prong 20 acts as a stop for the housing 10 in its lowest position. This feature is of particular advantage when replacing the housing, after having been withdrawn for cleaning purposes or after renewal, for the reason that it fixes the relation of its bottom to the 110

tooth brush support in the most desirable position. Furthermore, the provision of this slot permits the employment of an ordinary glass test tube which is of uniform diameter throughout its entire length as a housing. Heretofore in a holder, not providing for such a stop, a tube had to be used, either of tapering diameter, i. e. larger at the top, or one having a shoulder to rest upon arms 16 and 16^a or their equivalents, or else, frictional contact between the arms and the glass tube was entirely depended upon to maintain the same in position, which latter very often resulted in breakage of the glass and also necessitated the bending of the arms to fit the glass tube snugly. With the stop or prong 20 it is not necessary to have such a very snug fit between the glass 10 and arms 16 and 16^a, because the arms in this case act only as a guide to keep the same in a vertical position, the exact location being fixed by the stop.

While we have shown and described the housing 10 made of glass, we do not wish to limit ourselves to such, but may want to employ any other sanitary material which may be used to equal advantage.

Various other changes in the form, proportion and minor details of construction 30 may be resorted to without departing from the principle or sacrificing any of the ad-

vantages of the invention, as defined in the appended claim.

What we claim, as new, is:

A tooth brush holder, comprising a tubular housing of uniform diameter, closed at its top and open at its bottom, and a bracket stamped from a single piece of metal, consisting of a vertically disposed standard having arms at its upper end snugly embracing the said housing and slidably holding it in a position parallel to that of the said standard and in spaced relation thereto, the said housing being adapted to be removed from between the said arms by sliding upwardly only through the tops thereof, the lower end of the said standard being bent at substantially right angles and being cup-shaped to form a support for the lower end of the handle of a tooth brush, the said standard having a rigid prong projecting therefrom engaging the bottom of the said housing adjacent the said bracket and limiting the downward movement of the said housing without obstructing its opening, the said prong being cut out of the said standard and integral therewith at one end.

In testimony whereof we have hereunto set our hands and seals.

ROMAN WINOGRAD. [L. S.]
SAMUEL SHAKIN. [L. S.]
